UNITED STATES PATENT OFFICE.

JAMES C. POTTER AND JOHN JOHNSTON, OF PAWTUCKET, RHODE ISLAND, ASSIGNORS TO POTTER AND JOHNSTON MACHINE COMPANY, OF PAWTUCKET, RHODE ISLAND, A CORPORATION OF RHODE ISLAND.

TURRET-LATHE.

SPECIFICATION forming part of Letters Patent No. 772,477, dated October 18, 1904.

Application filed January 7, 1901. Serial No. 42,363. (No model.)

To all whom it may concern:

Be it known that we, JAMES C. POTTER, a citizen of the United States, and JOHN JOHNSTON, a subject of the King of Great Britain, both 5 residing at Pawtucket, in the county of Providence and State of Rhode Island, have invented a new and useful Improvement in Turret-Lathes, of which the following is a specification.

This invention has reference to an improvement in metal-working lathes in which the work is supported and rotated by the headstock and is operated on by a series of tools.

The present invention has particular reference to the driving mechanism of the lathe.

The invention consists in the peculiar and novel construction and the combination of the parts whereby the speed of the revolving work and the feed of the several tools may be adjusted and automatically controlled, as will be more fully set forth hereinafter.

In turret-lathes six tools are usually supported in the turret and successively presented to the work. Each tool requires to secure 25 the best work a specific feed of the tool and also the specific speed of the work best adapted to the tool.

The object of this invention is to provide means for adjusting the speed and feed for 30 each of the tools carried on the turret of a turret-lathe and when adjusted to reproduce a series of duplicates of the work by automatically controlling the speed and the feed.

Figure 1 is a side view of our improved 35 lathe, showing a turret tool-holder supported on the tool-slide. Fig. 2 is an end view of the head of the lathe. Fig. 3 is an end view as seen from the slide end of the lathe. Fig. 4 is a longitudinal vertical section of the head 40 of the lathe, showing two pairs of cone-pulleys and the mechanism for automatically controlling the belts on the cone-pulleys. Fig. 5 is a transverse sectional view of the head, showing the two cone-pulleys for driving the head-spindle and the two rear cone-pulleys 45 for operating the tool-slide and also the shipper connections for varying the speed of the head-spindle and the tool-slide. Fig. 6 is a

detail view illustrating the gearing for driving the spindle at different speeds. 50

Similar marks of reference indicate corresponding parts in all the figures.

In the drawings, A indicates the supporting-base of the lathe, preferably formed with closed sides and provided with doors to secure 55 convenient access to the interior; B, the headstock; C, the main tool-slide; D, the turret tool-holder, and E a cross-slide.

Power is applied, usually by a belt, to the pulley b, secured to the shaft b' of the lower cone-pulley b², which is connected by a belt b³ with the upper cone-pulley b⁴, on the shaft of which the pinion b⁵ engages with the gear b⁶, and this engages with the gear b⁷, secured to the back shaft b⁸, whereby rotary motion is imparted to the back shaft. On the back shaft b⁸ are two gears b²⁸ and b²⁹, mounted loose on the shaft. One of these gears is provided with a coupling b⁹ and the other with the coupling b¹⁰, and these gears engage, respectively, with the gear b¹¹ and the gear b¹² on the spindle b¹³. The clutch b¹⁴ is connected with the back shaft b⁸ by a spline and groove. When connected with the coupling b⁹, it drives the spindle b¹³ through the larger gear b¹¹, 75 and when the clutch is connected with the coupling b¹⁰ it drives the spindle through the smaller gear b¹². The clutch is operated by the rock-shaft b¹⁵, having at one end an arm or fork engaging with a circumferential groove on the clutch; and on the other end the operating-lever b¹⁶ is secured. The rock-shaft b¹⁵ is provided with a collar bearing against the inner end of the sleeve b¹⁷. The clamping-lever b¹⁸ is in screw-thread engagement with the threaded end of the shaft b¹⁵ and serves to clamp the same in the adjusted position. By this arrangement the spindle b¹³ may be rotated at high or low speed. Both of these speeds are under the control of the cone-pulleys b² and b⁴, by which the speed may be automatically varied. 85

The mechanism for operating the main tool-slide C and turret D is driven from the pulley b²⁰ on the shaft b' by means of a belt connecting the pulley b²⁰ with the pulley b²¹ on 90

the shaft of the upper back cone-pulley b^{22} , connected by the belt b^{23} with the lower back cone-pulley b^{24} . A graduated driving-pulley b^{25} is secured to the shaft of the lower back cone-pulley b^{24} and is connected by a belt with the graduated driving-pulley b^{26} on the shaft b^{27} , which extends to the mechanism operating the main tool-slide C and imparts motion to the same.

10 The mechanism operated by the shaft b^{27} may be of any one of the kinds heretofore used to convert the rotary motion of the shaft b^{27} into the desired reciprocating movement of the main tool-slide and the turret.

15 With the mechanism used to operate the main tool-slide we connect the shaft F, so that the same will make one revolution during the time required to use all the tools in the turret. With a six-sided turret the shaft F will 20 make one-sixth ($\frac{1}{6}$) of a revolution during one reciprocation of the turret and the main tool-slide.

On the shaft F is secured the drum f, and on the peripheral surface are adjustably secured two sets of plates f' f'. The outward-projecting edges of these plates f' f' are shaped to correspond with the variations of the speed of rotation of the work on the left-hand side of the drum f and the variations of 25 30 the speed of the main tool-slide and turret on the right-hand side of the drum during one reciprocation of the main tool-slide.

The variation of the speed of rotation of the work is secured through the arm f², pivotally supported near the heel f³ on a fixed part of the machine. The heel f³ has a roller which bears against the edges of the plates f' on the left-hand side of the drum f. The coiled spring f⁴ serves to maintain the contact between the heel f³ and the plates f'. The arm f² is provided with the segmental gear f⁵, engaging with the pinion f⁶, on the shaft of which is secured the gear f⁷, which engages with the rack-bar f⁸, one end of which is secured to the shipper f⁹, by which the belt b³, connecting the cone-pulleys b² and b⁴, is controlled. As the spindle b¹³ is driven through the cone-pulleys b² and b⁴ and the work is rotated by the spindle b¹³, the speed of rotation 35 40 45 50 55 is controlled through the shipper mechanism above described by the edges of the plates f' on the left of the drum f.

The plates f' on the right of the drum f control, through the arm f¹⁰ and the pinion f¹¹, the rack-bar connected with the shipper f¹², by which the belt b²³ is guided, and the variation of the speed of the shaft b²⁷ and through the same the feed of the tool-supporting turret are controlled.

60 The normal position of the belts b³ and b²³ is shown in the drawings near the ends of the cone-pulleys. The normal position of the belts may be at any point between the opposite ends of the cone-pulleys required to give 65 the desired normal speed of the lathe-spindle

and the normal feed or speed of reciprocation to the main tool-slide. To secure this end, the shaft supporting the pinion f⁶ and the gear f⁷, engaging with the rack-bar f⁸, and the shaft supporting the pinion f¹¹, on which 70 shaft the gear engaging with the rack-bar secured to the shipper f¹² is also supported, are both extended through the wall of the supporting-base. The ends of these shafts are squared or formed to fit a wrench. The 75 ratchet-wheels f¹³ f¹³ are secured on the ends of the two shafts, and the pawls f¹⁴ f¹⁴ are pivoted to the base A to engage with the ratchet-wheels f¹³, as is shown in Fig. 1.

As the cone-pulleys are, as shown in the 80 drawings, of such length as to allow an adjustment of the driving-belts of twenty-four inches, the ratchet-wheels f¹³ f¹³ are preferably provided with twenty-four teeth, and index-marks are placed on the ratchet-wheels. 85 By this construction and arrangement the normal position of the belts on the cone-pulleys may be accurately adjusted from the outside.

For reciprocating the main tool-slide C the mechanism shown in dotted lines in Fig. 1 90 may be employed, it comprising a worm G on the shaft b²⁷, which meshes with a worm-wheel H on the same shaft with the pinion h, that meshes with a gear I, having a crank i, that engages a lever K to vibrate the latter, 95 the lever K being connected by a pitman c with the tool-slide. The details of this mechanism need not be shown and described herein, as the same appear in our Patent No. 735,583, dated August 4, 1903, to which reference may 100 be made for a full understanding of the particular construction of said mechanism.

We have shown in the drawings the construction of the parts and their relations to each other in the (by us at this time) preferred form, but do not wish to confine ourselves to the exact construction of the parts and relations to each other as shown.

Having thus described our invention, we claim as new and desire to secure by Letters 110 Patent—

1. In a lathe, the combination of a part to be moved at variable speeds, belt-gearing for imparting motion to said part, a belt-shipper, a rack and gear for moving said shipper, and a cam-actuated lever for moving the gear. 115

2. In a lathe, the combination of a part to be moved at variable speeds, belt-gearing for imparting motion to said part, a belt-shipper, a rack and gear for moving said shipper, a 120 pinion connected with the gear, a lever having a rack meshing with the pinion, and a cam for operating the lever.

3. In a lathe, the combination of a spindle, a tool-slide, belt-gearing for driving the spindle at variable speeds, belt-gearing for moving the slide at varying speeds, and an automatic belt-shipping mechanism for each of 125 said belt-gearings.

4. In a lathe, the combination of a spindle, 130

a tool-slide, belt-gearing for driving the spindle at variable speeds, belt-gearing for moving the slide at varying speeds, a belt-shipper, a rack and gear for moving the belt-shipper, 5 and a cam-actuated lever for operating the gear.

5. In a lathe, the combination of a spindle, a driving-shaft, a variable-speed belt-gearing for transmitting motion from said shaft to the 10 spindle, one part of said belt-gearing being on said driving-shaft, a tool-slide, a variable-speed belt-gearing for moving said slide,

means for imparting motion from the driving-shaft to said second variable-speed belt-gearing, and means for automatically shifting the 15 belts of said belt-gearings.

In testimony whereof we have signed our names to this specification in the presence of two subscribing witnesses.

JAMES C. POTTER.
JOHN JOHNSTON.
